UNITED STATES PATENT OFFICE.

STANISLAW SZIMANSKI, OF NEWARK, NEW JERSEY.

DESIGN FOR A LAVALLIÈRE.

58,410.

Specification for Design.

Patented July 12, 1921.

Application filed January 6, 1921. Serial No. 435,518. Term of patent 3½ years.

To all whom it may concern:

Be it known that I, STANISLAW SZIMANSKI, a citizen of Poland, residing at Newark, in the county of Essex and State of New Jersey, have invented a new, original, and ornamental Design for a Lavallière, of which the following is a specification, reference being had to the accompanying drawing, forming a part thereof.

The figure is an elevational view of my lavallière, showing my design.

I claim:

The ornamental design for a lavallière, as shown.

STANISLAW SZIMANSKI.
